UNITED STATES PATENT OFFICE

110,042

DESIGN FOR AN AIR CIRCULATOR

Walter E. Willey, St. Louis, Mo., assignor to The Emerson Electric Mfg. Co., St. Louis, Mo., a corporation of Missouri

Application October 21, 1937, Serial No. 72,350

Term of patent 14 years

To all whom it may concern:

Be it known that I, Walter E. Willey, a citizen of the United States, residing at St. Louis, State of Missouri, have invented a new, original, and ornamental Design for an Air Circulator, of which the following is a specification, reference being had to the accompanying drawing, forming part thereof in which:

Fig. 1 is a perspective view of an air circulator embodying the present design; and,

Fig. 2 is a plan view of the air circulator shown in Fig. 1, the dotted line portions of Fig. 1 having been omitted.

A characteristic feature of my design resides in the ornamentation on the upper surface of the base.

I claim:

The ornamental design for an air circulator as shown and described.

WALTER E. WILLEY.
